UNITED STATES PATENT OFFICE.

PHILIP DIEHL, OF ELIZABETH, NEW JERSEY, ASSIGNOR TO THE SINGER MANUFACTURING COMPANY OF NEW JERSEY.

FEEDING MECHANISM FOR SEWING-MACHINES.

SPECIFICATION forming part of Letters Patent No. 319,800, dated June 9, 1885.

Application filed February 10, 1885. (No model.)

To all whom it may concern:

Be it known that I, PHILIP DIEHL, a citizen of the United States, residing at Elizabeth, in the county of Union and State of New Jersey, have invented certain new and useful Improvements in Feeding Mechanisms for Sewing-Machines, of which the following is a specification, reference being had therein to the accompanying drawings.

10 My invention relates to a feeding mechanism more particularly intended for that class of sewing-machines having the work-support in the form of an arm or horn, whereby the machines are adapted for sewing hollow or tubular articles.

15 My invention comprises a rock-shaft, the oscillations of which may be varied, an oscillating disk carried by said shaft, a feed-bar sliding vertically in said disk and provided 20 with a feed-dog, and a second shaft having a cam working in a slotted opening in said feed-bar, and thus serving to raise and lower the latter at proper intervals.

25 In the drawings, Figure 1 is a sectional side elevation of a sewing-machine embodying my invention. Fig. 2 is a section of the same through the vertical portion of the bracket-arm. Fig. 3 is a cross-section through the forward end of the work-supporting arm, showing 30 the feed-bar and its carrying-disk in elevation. Fig. 4 is a central section through the forward end of the work-supporting arm. Fig. 5 is a side view of the oscillating disk and part 35 of its rock-shaft, and Fig. 6 a face view of said disk. Fig. 7 is a detail face view of the feed-bar and its feed-dog, and Fig. 8 a side view of the same.

40 I have herein shown my invention as applied to a sewing-machine having a shuttle-carrying rock-shaft, A, operated in the manner described in Patent No. 208,838, dated October 8, 1878, and a feeding rock-shaft, B, receiving its movements from a cam on the upper shaft of the machine by the mechanism 45 described in Patent No. 229,629, dated July 6, 1880, both of these patents having been granted to L. B. Miller and myself. The movements of the rock-shaft B are capable of being varied by a regulator, C, as fully set forth in 50 the patent last referred to. I do not, how-

ever, wish to be understood as limiting my invention to the particular mechanism above referred to for operating the shafts A and B, nor is it necessary that the shaft A should be a rock-shaft, as it might have a continuous rotary instead of an oscillatory movement and still properly perform its functions, as hereinabove described, in operating the feed-bar. The shaft A is provided at its forward end with a shuttle-driver, a, and just back of said 55 driver is a feed-cam, a'. The rock-shaft B carries at its forward end a disk, b, which is herein shown as being formed integral with said shaft. The disk b is provided with an undercut recess, b', forming guiding-ways, and 60 in said recess is fitted the vertically-sliding feed-bar D, and to the latter is attached the feed-dog E. The cam a works in a slotted opening, d, in the feed-bar D, said cam in its 65 rotations impinging against the horizontal 70 walls only of said opening, thus imparting positive vertical movements to said bar at proper intervals.

75 It will be understood that the movements of the two operating shafts are so timed that the oscillating disk by which the feed-bar is moved horizontally will be stationary, or nearly so, during the times when said bar is being moved vertically by the cam a', and thus a feed which is practically a four-motioned one and which 80 is positive in all directions will be produced.

As the oscillating movements of the shaft B, and thus of the disk b carried thereby, may be varied at will, it is obvious that the horizontal or feeding movements of the feed-bar 85 and its dog may be regulated to produce any desired length of stitch.

I claim as my invention—

1. In a sewing-machine, the combination, 90 with a rock-shaft having a disk, of a feed-bar adapted to slide vertically in ways in said disk, said bar carrying a feed-dog and being provided with an opening, a cam working in said opening, and a shaft by which said cam is carried, substantially as set forth.

95 2. In a sewing-machine, the combination of a rock-shaft having a disk, a regulator for varying the movements of said rock-shaft, a feed-bar movable vertically in said disk and having an opening, a feed-dog carried by said 100

bar, a cam working in said opening, and a shaft by which said cam is carried, substantially as set forth.

3. The combination, with the rock-shaft A,
5 having cam a' , of the rock-shaft B, having the recessed disk b , the feed-bar D, adapted to slide vertically in said disk, and having the opening d and the feed-dog E, substantially as set forth.

In testimony whereof I affix my signature to in presence of two witnesses.

PHILIP DIEHL.
